[57] CLAIM

The ornamental design for a safety razor handle, as
shown and described.

DESCRIPTION

FIG. 1 is a front elevational view of a safety razor handle
showing my new design;

FIG. 2 is a side elevational view of the handle of FIG.
1; and

FIG. 3 is a rear elevational view of the handle of FIG.
1.

The broken line showing of a cartridge is illustrative of
environment only.

FIG. 1

FIG. 2

FIG. 3
